UNITED STATES PATENT OFFICE

140,414

DESIGN FOR A CONTAINER FOR BOTTLES AND OTHER ARTICLES

William F. Wise, Detroit, Mich., assignor to The Aviation Corporation, Detroit, Mich., a corporation of Delaware

Application September 13, 1944, Serial No. 115,288

Term of patent 14 years

(Cl. D58—12)

To all whom it may concern:

Be it known that I, William F. Wise, a citizen of the United States, residing at Detroit, in the county of Wayne and State of Michigan, have invented a new, original, and ornamental Design for a Container for Bottles and Other Articles, of which the following is a specification, reference being had to the accompanying drawings, forming a part thereof, wherein

Figure 1 is a perspective view of a container
for bottles and other articles, showing my new design;

Figure 2 is a side view; and
Figure 3 is an end view thereof.

I claim:

The ornamental design for a container for bottles and other articles, substantially as shown.

WILLIAM F. WISE.
